UNITED STATES PATENT OFFICE.

GEORGE H. WOMELSDORF, OF PHILADELPHIA, PENNSYLVANIA, ASSIGNOR TO RENO MANUFACTURING COMPANY, OF PHILADELPHIA, PENNSYLVANIA, A CORPORATION OF PENNSYLVANIA.

JAR-CLOSURE.

1,105,391.

Specification of Letters Patent. Patented July 28, 1914.

Application filed June 27, 1910. Serial No. 569,068.

To all whom it may concern:

Be it known that I, GEORGE H. WOMELSDORF, a citizen of the United States, residing in Philadelphia, Pennsylvania, have invented certain Improvements in Jar-Closures, of which the following is a specification.

One object of my invention is to provide a closure for containers which shall be capable of acting as a sealing ring to prevent the admission of air to or the leakage of liquids from the interior thereof, and which shall be inexpensive to manufacture as well as of such a composition as not to deteriorate with time.

I further desire to provide a jar closure or sealing device of such construction that when applied to a jar or other container substantially full of liquid it shall displace any air which might otherwise be confined between it and the top surface of said liquid.

It is also desired that the construction of the closure shall be such that one portion of it shall serve as a guide to suitably position the other portion on the edge or sealing surface of the container.

These objects and other advantageous ends I secure as hereinafter set forth, reference being had to the accompanying drawings, in which:—

Figure 1, is a vertical section of a well known form of jar showing my invention as applied thereto; Fig. 2, is a vertical section of a slightly modified form of my improved closure or sealing ring; Fig. 3, is a perspective view of the form of my sealing ring or closure shown in Fig. 1, and Fig. 4, is a vertical section of a ring made of a single sheet of material.

In the above drawings, 1 represents a glass jar having an exteriorly threaded neck 2 on which may be screwed a suitably threaded metallic cover 3, within whose top is confined the glass or porcelain disk.

My improved closure consists of a disk 5 having its edges 6 flanged and slightly flared and provided with a compressible sealing ring 7 permanently held, either by some adhesive or by being made integral with the disk (as in Fig. 4), to the upper outside edge of the flanged portion 6. While the disk and its flange are made of any relatively compact pulp board or equivalent material such as finely ground cork board or jute, the

ring 7 is of relatively porous, loosely compacted and compressible pulp which is first saturated with some substance as glycerin for maintaining it soft and pliable and with the disk 5, is thereafter coated and to some extent impregnated with a mixture of collodion and castor oil. This coating is of such a nature as to effectually seal the glycerin within the ring 7 and at the same time make both it and the flanged disk impervious to moisture and air. While of course collodion might be used alone, I have found that the castor oil or some other non-drying oil renders it more or less soft and sticky, and maintains it in this condition, so that the closure to which this compound is applied most perfectly fulfills its functions in preventing leakage of air or liquid around its edges or through its body. The disk and its flange are primarily valuable in serving as a guide or centering device for the ring 7 so that in applying the device to a jar, this latter portion is necessarily centered upon the top edge of the neck 2 and is directly confined between it and the porcelain disk 4 when the cap 3 is applied. The screwing down of said cap prevents all leakage of liquid past the sealing ring owing to the substances with which it is coated and impregnated, and thus forms what is practically a perfect seal with the two surfaces between which it is mounted.

In some forms of jars the porcelain disk may be omitted so that the ring 7 makes its seal between the metallic cap 3 and the top edge of the jar neck. The flanged disk 5 then prevents all access of the material within the jar to the metal of the cap and thus prevents all corrosion of said metal and possible injury to the contents of the jar. Another advantage of the construction is due to the fact that the insertion of the flanged disk into the body of liquid in the jar when the ring is applied thereto, displaces any air bubbles which would otherwise be caught between the cover and the surface of the liquid; it being noted that the disk 5 should be plane or downwardly convex so that the escape of the air is assured.

As shown in Figs. 1 and 3, the outer edge of the ring 7 is slightly beveled in order that it may not bind on the inside surface of the cap, although if desired, I may construct

this ring as shown at 7^a in Fig. 2, with a vertical outside edge.

The device as a whole may in some instances be used as a closure without any other form of cap, in which case it may be applied to a tumbler or jar as shown in Fig. 1, and the ring 7 is pressed down into intimate contact with the top edge of such container so that the adhesive material with which said ring is coated forms a tight permanent seal; it being understood that the joint between the ring and the flanges of the disk 5 is a tight one; there being either some adhesive or sealing material used to join these two parts, or the ring may be forced onto the disk and the whole merely coated with the compound above described.

As shown in Fig. 4, the ring is formed of a single sheet of pulp board pressed into shape, although the material of which the ring is made is originally of uniform thickness and made of loosely compacted material. I so operate on it that the sealing portion 7^b is unaltered as to its thickness while the disk 5 and its flange are compressed so as to be stiff and relatively thin. As before the part 7^b is preferably filled with material for keeping it soft and pliable and thereafter the whole structure is coated with

30 collodion as above.

I claim;

1. A sealing closure consisting of a disk of relatively compact stiff material having an integral sealing portion permanently connected to it and consisting of loosely compacted material.

2. A sealing closure consisting of a disk of relatively compact stiff material having an integral sealing portion permanently connected to it and consisting of loosely compacted material impregnated with a substance for maintaining it soft and pliable.

3. A sealing ring of loosely compacted material impregnated with glycerin and

coated with a mixture of an oil and colloidion.

4. A closure consisting of a disk shaped body of relatively dense sheet material having an integral sealing portion of loosely compacted material coated with a mixture of an oil and collodion.

5. A sealing cap for bottles, embodying an external clamping member and an integral internal packing member, said packing member having a relatively dense central portion and a relatively soft and elastic margin to form the seat for the mouth of the bottle.

6. A sealing cap for bottles, embodying an external clamping member and an integral internal packing member, said packing member having a relatively dense and thin center and an annular margin which is relatively thick, soft and elastic to form the seat for the mouth of the bottle.

7. A sealing cap for bottles, embodying an external cup-shape metal cap and an internal packing of compressed and bonded granulated cork, said packing having a relatively dense impervious center and an annular margin which is relatively soft and elastic to form the seat for the mouth of the bottle.

8. A sealing cap for bottles, embodying an external cup-shaped sheet metal cap member and a molded granular packing member therein having a central depression in its face and an annular margin which is soft and elastic to form the seat for the mouth of the bottle.

In testimony whereof, I have signed my name to this specification, in the presence of two subscribing witnesses.

GEORGE H. WOMELSDORF.
